UNITED STATES PATENT OFFICE.

ALICE H. FLANDERS, OF CHICAGO, ILLINOIS, ASSIGNOR TO A. H. FLANDERS COMPANY,
OF CHICAGO, ILLINOIS, A CORPORATION OF ILLINOIS.

DESIGN FOR A WOMAN'S BLOUSE.

54,397.

Specification for Design.

Patented Feb. 10, 1920.

Application filed May 29, 1919. Serial No. 300,731. Term of patent $3\frac{1}{2}$ years.

To all whom it may concern:

Be it known that I, ALICE H. FLANDERS, a citizen of the United States, residing at Chicago, in the county of Cook and State of Illinois, have invented a new, original, and ornamental Design for a Woman's Blouse, (No. 368,) of which the following is a specification, reference being had to the accompanying drawing, forming part thereof.

Fig. 2 is a view in elevation of a portion of the back, the same slightly enlarged.

I claim:

The ornamental design for a woman's blouse, as shown.

ALICE H FLANDERS.
